INVENTOR

James W. Boyce,
by
Arthur B. Jenkins,
ATTORNEY

UNITED STATES PATENT OFFICE.

JAMES W. BOYCE, OF HARTFORD, CONNECTICUT.

GOLF CLUB.

Application filed January 3, 1927. Serial No. 158,556.

My invention relates to the class of devices employed for propelling a ball, more especially in the well known game of golf, and an object of my invention, among others, is the production, more especially, of that form of a club known as a putter that shall be particularly useful and efficient for the purposes for which it is made.

One form of a putter embodying my invention and in the construction and use of which the objects herein set out, as well as others, may be attained, is illustrated in the accompanying drawings, in which—

Figure 1 is a side view of my improved putter, shown with the handle broken off.

Figure 2 is a front view of the same.

Figure 3 is a top view.

In the accompanying drawings the numeral 5 indicates a socket in which a handle 6 may be secured in any desired manner, this socket having head supporting arms 7 extending divergently therefrom, and as shown in Figure 3. A head 8 is supported at the end of each of said arms and this head 25 may be of any form suitable for the special use to which it is intended to be put. As shown herein each of said heads has a striking face 9 and these faces preferably slope backwardly from the bottom of the head toward the top and the bottoms 10 of the heads 30 preferably slope downwardly from the faces 9, and as shown in Figure 2 of the drawings.

An important feature of my invention resides in the two heads spaced apart and located on opposite sides of a plane passing axially through the handle in a vertical direction, the term "vertical" being employed with respect to the position of the putter when in use. A bridge 11 is rigidly connected with and extends between the backs of the heads 8, and as shown in Figure 3. This bridge is comparatively narrow, when viewed from the top, and it may be of such width in a vertical direction as may be desired. It forms not only a stiffening and strengthening feature for the putter, but being comparatively thin it comprises a means whereby the putter may be accurately placed with respect to the direction in which a ball is to be driven, thereby insur-

ing precision in the operation. This bridge, in fact, forms a sight line and, if desired, in order to emphasize this feature an arrow 12 may be placed upon the bridge, and this 55 may, as shown in the drawings herein, be extended across and beyond the bridge and onto the heads 8, the barbs of the arrows, in fact, being located on said heads and the shafts of the arrows extending across the 60 bridge.

While I consider that the bridge 11 is an important feature of the invention, yet I contemplate instances wherein such bridge may be dispensed with without departing 65 from the spirit and intent of the invention.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above 75 set out.

I claim—

1. A golf club including a support, arms branching from said support, a head formed at the end of each of said arms, and a bridge 80 extending between said heads.

2. A golf club including a support, arms branching from said support, a head formed at the end of each of said arms, each head having a striking face, and a bridge extending between said heads in a direction substantially at right angles to the axis of said support.

3. A golf club including a support, arms branching from said support, a head formed 90 at the end of each of said arms, a bridge extending between said heads, and a sighting element extending lengthwise of said bridge.

4. A golf club including a support, arms branching from said support, a head formed at the end of each of said arms, a bridge extending between said heads in a direction substantially at right angles to the axis of said support, and a sighting element extending 100 lengthwise along said bridge and onto said heads.

5. A golf club including a support, arms branching from said support, and a head formed at the end of each of said arms, said heads being spaced apart and each head having a striking face oppositely arranged to the striking face on the other head.

6. A golf club including a socket support, arms extending from said support in diver-

JAMES W. BOYCE.
